UNITED STATES PATENT OFFICE.

CARL A. NELSON, OF JOHNSONBURG, PENNSYLVANIA.

ELECTRIC-FUSE PLIERS.

Application filed May 16, 1922. Serial No. 561,389.

To all whom it may concern:

Be it known that I, CARL A. NELSON, a citizen of the United States, residing at Johnsonburg, in the county of Elk and 5 State of Pennsylvania, have invented new and useful Improvements in Electric-Fuse Pliers, of which the following is a specification.

The object of my said invention is the 10 provision of pliers designed to enable an electrician to safely handle fuses when removing or placing fuses, particularly fuses of small size.

To the attainment of the foregoing, the 15 invention consists in the improvement as hereinafter described and definitely claimed.

In the accompanying drawings, forming part of this specification:—

Figure 1 is a side elevation of a device 20 constructed in accordance with my invention.

Figure 2 is a longitudinal section of the same.

Figure 3 is a diametrical section of the 25 handle member of the device.

Figure 4 is a cross-section of same.

Figures 5 and 6 are enlarged views illustrating the peculiar construction of the jaws comprised in the device.

30 Figures 7, 8 and 9 are cross-sections on the lines 7—7, 8—8 and 9—9, respectively, of Figure 2.

Similar numerals of reference designate corresponding parts in all of the views of 35 the drawings.

Among other elements my novel device comprises a handle 1 of wood fiber or other appropriate dielectric material. Exterioly the said handle 1 is of angular form in 40 cross-section, and interiorly the handle 1 is threaded as indicated by 2 and is provided at its lower end with a chamber 3. Metallic bands 4 and 5 are mounted on the lower and upper portions of the handle 1 to lessen the 45 liability of the handle splitting when the device is in use.

In addition to the handle 1 the device 50 comprises a threaded shank 6, of wood fiber or other dielectric material, and rounded at its lower end as indicated by 7*. On the lower portion of the said shank 6 is appropriately secured a sleeve 7 of brass or other suitable metal or alloy, and integral with the said sleeve 7 are jaws 8 which as shown 55 in Figures 5, 6 and 7 are of peculiar construction. In this connection it will be

noticed that the jaws are formed of strips of brass or other appropriate metal or alloy, each of the jaws having an outer portion 9 integral with the sleeve 7, and an inner portion 10 spaced from the portion 9, and also having a shoulder 11, an inner concave portion 12, and an outer correspondingly curved portion 13, the said portions 12 and 13 being joined by a bight 14 at the lower extremity of the jaws. The inner portions 10 of the jaws are joined and curved as indicated by 15. It will also be noticed that the jaws and the sleeve 7 are so arranged as to afford a triangular space 16 at the 70 lower end of the sleeve 7. In this connection it will be understood that the shank 6 is rounded or ball like at its lower end 7*, in order to afford more contraction space.

Movable rectilinearly on the sleeve 7 and 75 by the handle 1 is a tubular follower 17. Disposed below and opposed to the lower end of the follower 17 is a ring 18 of wood fiber or other appropriate dielectric material, the said ring 18 being roughened at its outer side and being interiorly of angular form in cross-section. The follower 17 which is preferably of wood fiber or other dielectric material can be held by the fingers of the operator, and when the handle 80 1 is turned in the proper direction it works down on the threaded shank 6, and moves the follower 17 before it, so that the ring 18 preceding the follower presses the jaws together in such manner as to clamp the same on a fuse or the like. The joint or connection 15 between the jaws renders the jaws resilient so that when the follower 17 is retracted the jaws will spring open as 85 shown in Figure 5.

It will be apparent from the foregoing that through the medium of my novel device fuses and particularly small fuses can be handled with facility and with perfect safety to the operator.

Having described my invention, what I claim and desire to secure by Letters-Patent, is:—

1. Pliers comprising a threaded shank, 105 spring jaws connected with said shank and having outer and inner spaced portions, the outer portions being shouldered, a tubular handle interiorly threaded and surrounding and engaging the shank, and means surrounding the jaws and interposed between the end of the handle and said shouldered portions of the jaws and movable rectiline-

110

arly by the handle on rotation thereof to close the jaws and hold the same in closed position.

2. Pliers comprising a threaded shank, 5 spring jaws connected with said shank and having outer and inner spaced portions, the outer portions being shouldered, a tubular handle interiorly threaded and surrounding and engaging the threaded shank, and means 10 surrounding the jaws and movable rectilinearly by the handle on rotation of the

latter to close the jaws and hold the same in closed position; said means being in the form of a ring interiorly of angular form in cross-section surrounding the upper portions of the jaws and arranged to be stopped by the exterior shoulders thereof, and a tubular follower interposed between the tubular handle and ring.

15 In testimony whereof I affix my signature.

CARL A. NELSON.
